UNITED STATES PATENT OFFICE.

CARL TOBER, OF BERLIN-KARLSHORST, GERMANY.

BRAIDING MACHINE.

Application filed January 31, 1921. Serial No. 441,422.

(GRANTED UNDER THE PROVISIONS OF THE ACT OF MARCH 3, 1921, 41 STAT. L. 1313.)

To all whom it may concern:

Be it known that I, CARL TOBER, a citizen of Germany, residing at Berlin-Karlshorst, Prinz Adalbertstr. 10, Germany, have invented certain new and useful Improvements in Braiding Machines (for which I have obtained a patent in Germany based on an application filed on June 8, 1917; in Switzerland based on an application filed March 10, 1920; in Czechoslovakia based on an application filed May 7, 1920; in Italy based on an application filed June 30, 1920; in Belgium based on an application filed Febr. 10, 1920; in Luxembourg based on an application filed Febr. 5, 1920; in Austria based on an application filed Jan. 22, 1920; in France based on an application filed Febr. 19, 1920; in Holland based on an application filed March 11, 1920; and in Great Britain 20 based on an application filed July 2, 1920), of which the following is a specification, reference being had therein to the accompanying drawing.

My invention relates to braiding machines 25 having bobbin slides continuously moved by a roller system and more particularly consists in an improvement of the means for moving the bobbin slides and passing the outer threads through the roller system.

The roller system in this type of machine 30 has well-known advantages over former types in that there are no segmental toothed wheels or couplings and in that it is proof against the falling in of torn threads and 35 thread ends; it has however the disadvantage that the outer threads in the path beneath the inner bobbins when passing between the driving roller and slide roller (bobbin roller) are subjected to considerable 40 pressure.

In order to prevent so far as possible damage to the outer threads, the rollers are in a well known manner provided at their circumference with a yielding material, such 45 as rubber, leather or the like; this does not however substantially diminish the pressure on the outer threads as the power necessary to move the slides transmitted from the driving rollers to the slide rollers is not altered 50 thereby.

It has been found in machines of this type that the cause of the great pressure on the thread when the slide track is constructed in the usual manner (the slide track 55 poses considerable resistance to the move-

ment of the slides and so to the driving and slide rollers) lay in the fact that the slide track formerly employed in combination with the said roller system was stationary; it was contained in a stationary casing which was provided with a waved slot corresponding with the waved path of the outer threads. The slide track ring was for this purpose formed of at least two completely separated portions; the upper portion could be connected to the machine frame only outside of the outer bobbins and the lower portion only inside of the outer bobbins which revolve about the braiding axis. It was found in practice that the slide track segments situated alternately in said upper and lower portions could not be made to register with such exactness that the slides could without shock pass from the upper to the lower portion and vice versa; this is due to the fact that even though the track were formed simultaneously on the separated parts, the manufacture is difficult on account of springiness and the mounting of the separated parts is a source of error.

In the well-known machines of this type having eight inner bobbins and eight slides together passing 64 times from one ring to the other, there occur during one revolution only about the braiding axis i. e., with only 160 revolutions per minute in round numbers 10,000 passages per minute making in round numbers six million passages in ten hours. It will easily be seen that a small deviation only of the segments from each other would result in shocks to the slide which shocks would dissipate considerable power owing to their great number occurring per unit of time. Both this power and the power necessary to overcome the normal friction of the slide must be transmitted by the driving and slide rollers to the slides. The total of these forces causes great pressure on the outer threads when passing between the rollers.

The roller system driving the inner bobbins is therefore combined with a well-known slide track which turns in the same direction as the outer threads revolving about the braiding axis; the slide track 105 serves as a bearing to the slides which turn in opposite direction to the inner bobbins revolving in the opposite direction; this as is known renders it possible to connect all the slide track segments to an adjacent comp-

mon base whereby the slide tracks can easily be made with such exactness that the slides will move without shock; this obviates any absorption of the power to be transmitted by the rollers which was hitherto absorbed by the shocks of the slides in their track.

It will then only be necessary to transmit to the driving and slide rollers the power required to overcome the normal friction of the slide which results in relieving the outer threads passing between the rollers.

The novelty of my invention therefore consists in the novel combination of the well-known roller system with the well-known revolving slide track; which combination produces the novel effect that the outer threads each time they pass between the rollers of the roller system are relieved, whether the rollers are or are not provided with an elastic covering and with recesses at the circumferences, and whether a friction roller or toothed wheel drive is provided for the driving rollers.

Compared with braiding machines of a well-known type having a roller system, my machine possesses the further considerable advantages that the threads are further relieved and a shifting of the roller system relative to the temporary position of the outer threads is avoided when the inner bobbin slides and the slide track are arranged between the inner bobbins and the braiding axis.

This further relief of the thread is obtained by arranging the slides and the slide track between the inner bobbins and the braiding axis as the slides and track can be brought nearer to such axis; the frictional resistance therefore of the slides against their track is considerably lessened because of the considerably diminished centrifugal force of the slides; the rollers therefore which drive the slides and between which the threads pass also exert a smaller pressure upon the rolled thread than if the slide track were arranged outside of the inner bobbins.

The relative displacement of the roller system occurs when the toothed wheels or other machine elements which drive the roller system are omitted. In that case, the rollers would remain behind and the threads be deflected out of their position thus being stretched. The wear of the toothed wheels or other machine elements is considerably lessened in that the slides and the slide track are arranged inside of the inner bobbins as near to the braiding axis as possible. Thus, the power necessary to displace the slides is considerably reduced and thereby also the wear of the machine elements, while the position of the rollers relative to the outer threads remains unaltered.

Braiding machines with oppositely re-

volving rows of bobbins in which the inner bobbins and the slide track are arranged between the inner bobbins and the braiding axis are indeed known; in the present case, however, there is no roller system for operating the inner bobbins and for leading the outer threads rotating in the opposite direction between the rollers of the roller system rolling on each other.

My invention is illustrated in the accompanying drawings in which Figure 1 is a vertical section through a machine having two curved tracks and in which to the right of the axis a driver roller and a slide roller are omitted for the sake of clearness.

Fig. 2 is a plan of the left half of Figure 1;

Figure 3 is a view showing the internal portions of the machine shown in Figure 1 in which can be seen the driving rollers with the slide rollers and slides as well as the slotted slide track; Figure 4 is an elevation of the slide track ring, and Fig. 5 an enlarged reproduction of the right-hand side of Fig. 1.

1 is a base plate provided at its centre with a stationary sleeve 17 upon which revolves the hub 19 of a brake drum 21. Fast to the hub 19 is the outer rotating carrier 7 carrying the outer bobbins 18, threaded guides 3, 4 and 5 and a slotted ring 24 rotating with it. The said parts receive their revolving movement about the braiding axis through the bevel wheels 34 and 36 mounted respectively on the hub 19 and the shaft 29 driven by means of the belt pulley 39.

The slides 37 rotate along the guide track 41 provided on ring 24 and in opposite direction thereto. They carry the inner bobbins 20 and are driven by a roller system in the following manner. The bevel wheel 36 is also in mesh with the bevel wheel 42 arranged opposite the bevel wheel 34. The bevel wheel 42 thus rotates in opposite direction to the bevel wheel 34 and is mounted on a hollow spindle 25 revolving within the stationary sleeve 17. 26 is a plate fixed on the upper end of the spindle 25 on which plate are mounted pivots 27 carrying arms 28 movable thereon. Each arm carries a spindle 31 on which are mounted either integrally or secured to each other the smaller driven roller 32 and the larger driving roller 30.

The driven roller 32 on the rotation of the plate 26 runs on a track 33 which is mounted on the sleeve 17 and is therefore stationary. Both rollers 32 and 30 besides their revolving movement about the braiding axis, are rotated about their common axis. Both the revolving movement and the rotating movement of the roller 30 are transmitted to the slide rollers 23, which are mounted on stationary spindles 22 on the

slides 37 which carry the inner bobbins 20; the revolving movement of the plate 26 about the braiding axis is transmitted to the rollers 23 and thereby to the slides 37 with their bobbins 20. The direction of rotation of the rollers 30, the slide-rollers 32 and of the advancing movement imparted to the slides 37 is indicated by the arrows in Fig. 3, whereas the paths of the threads 10 from the outer bobbins 18 are indicated by the broken lines in Fig. 2.

Figure 4 shows the slotted ring 24 in elevation in which construction the track 41 is cast with the casing. This need not be the case, however, thus for the sake of economy the track 41 may consist of a bronze segment and the casing 24 be made of cast iron. The essential point of the well-known revolving slide track segments 20 is that all such segments should have a common contiguous basis at the underside of the casing 24; this is because the outer threads only receive to and fro movements corresponding to the slots 40 relative to the 25 ring while both the outer threads and the casing move about the braiding axis in the same direction in contradistinction to the well-known construction in which the outer threads have both a to and fro movement 30 and a revolving movement about the braiding axis relative to the stationary casing,

i. e., a wave as on a fixed casing which was completely separated into two parts.

What I claim is:

1. In a braiding machine a plurality of 35 outer bobbins, a rotatable carrier therefor, a plurality of slides adapted to revolve relative to said carrier in opposite direction thereto, inner bobbins carried by said slides, a set of rollers for operating the said slides, 40 a track on the said carrier for the said slides and means for rotating the said set of rollers.

2. In a braiding machine, a plurality of outer bobbins, a rotatable carrier therefor, a plurality of slides adapted to revolve relative to said carrier in opposite direction thereto about the braiding axis, inner bobbins carried by the said slides, a track on the said carrier for the said slides, the said track and the said slides being arranged between the said inner bobbins and the braiding axis, a set of rollers for operating the said slides, and means for rotating the said set of rollers. 45 50

In testimony whereof I have hereunto 55 affixed my signature in the presence of two witnesses.

CARL TOBER.
